UNITED STATES PATENT OFFICE.

CYRUS W. SALADEE, OF CLEVELAND, OHIO.

ROAD-WAGON.

SPECIFICATION forming part of Letters Patent No. 434,299, dated August 12, 1890.

Application filed April 1, 1890. Serial No. 346,216. (No model.)

To all whom it may concern:

Be it known that I, CYRUS W. SALADEE, a citizen of the United States, residing in the city of Cleveland, State of Ohio, have invented 5 certain new and useful Improvements in Spring-Platforms for Road-Wagons, of which the following is a specification embodying said invention, and which is more specifically pointed out in the appended claims.

10 The invention consists in the employment of side springs arranged parallel to each other and extended to the axle from a fifth-wheel device secured to the bottom frame of the body in contradistinction of side springs that 15 are radially extended from the bottom of the body to either axle, as heretofore adopted.

The object of my invention is to improve the appearance of the structure, to secure the short turning of the vehicle, and to simplify 20 its manufacture, all as hereinafter more fully shown and described.

In the drawings, Figure 1 is a side elevation of a complete vehicle, in which is represented my said improvements. Fig. 2 is a detached plan view of the front platform. Fig. 3 is a detached plan view of the rear platform seen in Fig. 1, whereby the means for connecting the springs to prevent the rotation of this axle is disclosed. Fig. 4 is a rear elevation 25 of the hind axle. Fig. 5 is a front elevation of the forward axle, as seen in Fig. 1. Fig. 6 is a detached front view of the front cross-bar seen in Fig. 2, with a fifth-wheel in position and the side and center springs seen 30 in cross-section. Fig. 7 is a detached front view of the rear cross-bar seen in Fig. 2, with the side and center springs seen in the cross-section. Fig. 8 is a side elevation of the vehicle wherein the terminal ends of the springs 35 are rigidly secured to the axle. Fig. 9 is a detached plan view of the rear platform seen in Fig. 8. Fig. 10 is a plan view of the front platform, omitting the central spring seen in Fig. 2. Fig. 11 is a front elevation of the 40 cross-bar F seen in Fig. 10. Fig. 12 is a front elevation of the rear cross-bar H seen in Fig. 10. Fig. 13 is a detached side view of a piece of the body-sill, showing the manner 45 of securing the cross-bars T seen in Fig. 9 to the bottom frame of the body.

These spring-platforms are independent of each other, and either may be used to support one end of the body, while some other

well-known means may be employed to support the opposite end.

55

I proceed with the construction of these spring-platforms respectively as follows, and first, as to the front platform, it is my purpose to construct this platform either with or without the central spring seen in Figs. 1 and 2. 60 For the cheaper class of vehicles I shall make this front platform as seen in Figs. 8 and 10. Side springs A A have their rear ends connected by cross-bars F and H, which may be made of wood; but I prefer them of steel 65 plates, as shown in Figs. 11 and 12, whereby to form the bridge-brace represented in these figures at F F' and H H'. On the front bar F is carried the fifth-wheel coupling E E', and the king-bolt I, passing through the cross-sill 70 of the body, connects the platform to the bottom of the body, as seen in Figs. 8 and 11. The rearward bar H' is supported upon and carried by a roller-bearing suspended from the bottom of the body by the dependent 75 brackets D³. The front ends of the springs in this instance are rigidly clipped to the under side of the axle, as at J, Figs. 8 and 10. The platform turning upon the king-bolt I will cause the cross-bar H' to sweep around 80 upon the oblong roller D⁴, as clearly shown in last-named figures. By the construction of this platform as above described it will be understood by reference to Fig. 8 that the vibration of the springs will rotate the axle; 85 but I can obviate this, when desired, in the better class of vehicles by employing the central spring A', (seen in Figs. 1 and 2,) in which case the terminal eyes of the side springs are pivotally connected to the top of the axle and 90 the center spring to the bottom, as at S' S²; Fig. 1. The side springs in this instance are connected to the cross-bars F H and otherwise connected to the body, as already described. The rear end of the center spring A' is supported upon a truss-brace H², more clearly 95 seen in Fig. 7, and a curved brace A² further secures the rear end of this spring to the cross-bar F', Fig. 6. In this case the rear cross-bar H' is carried upon the friction-plate D, more 100 clearly seen in Fig. 1. This plate has its rear end bent up and bolted to the center sill of the body, as at 3 and 4. Its forward end is extended to and takes the king-bolt I. This plate is further supported by the hanger-bolt 105 D², Fig. 1. Thus when turning the platform

on the king-bolt I the rear bar II' sweeps around on the friction-plate D. The pivotal connection of the side and center springs is further shown in Fig. 5.

5 The rear platform for the cheaper grade of work is seen in Figs. 8 and 9. In this instance the inner ends of the side springs B, which are parallel to each other, as before described, are bolted directly to the under surface of the side sills of the body, or, preferably, upon the outer ends of the cross-bars T T, and their terminal ends rigidly clipped to the axle, as at L'. The spring-brace or axle-stay B' has its inner end rigidly secured to the under side of the side spring, and with the latter firmly clipped and bolted to the under side of the body-sill or cross-bars T T. The rear end of the axle-stay B' is rigidly clipped to the under side of the axle at L' the same as the side spring. When preferred, the latter may be shackled to the axle, while the axle-stays are rigidly connected thereto.

For the purpose of omitting the piercing of holes directly through the cross-bars whereby to secure them to the body, I use an under plate T', Figs. 8 and 9, through which the bolt-holes 1, 2, 3, and 4 are pierced, as in Fig. 9, and then secured to the body-sill N, as in Fig. 11.

30 As seen in Figs. 1, 3, and 4, the side springs B have their inner ends bolted directly to the side sill of the body and their rear ends shackled to the under side of the axle at K, which is arched up at this point, so as to carry the terminal eye of the side spring in a higher plane than the axle-stay B', which latter is shackled to the depressed portion of the axle, as at K', which admits of carrying the rear ends of the side springs and axle-stay in different horizontal planes. The front ends of the axle-stays B' are in this case secured to the side springs or bottom of the body in a lower plane than the side springs, and are preferably secured to a downwardly-curved brace B², formed from the underplate of the side springs, as seen in Figs. 1 and 3. A cross-bar T also connects the inner ends of the axle-stays, as at C', C², and C³. (See Fig. 3.) A vertical spool C', Fig. 1, is interposed between the bar T and the under side of the spring B at this point. The springs and stays being thus secured in different horizontal planes, the rotation of the axle by their vibration is prevented.

55 Without limiting my claims to the precise arrangement of the several parts shown and described, I claim—

1. The combination, in a front spring-platform for road-wagons, side springs extended from the bottom of the body to the axle, the rear ends of said springs being united by two cross-bars, the front bar of the pair connected to the body by a king-bolt or fifth-wheel device and the rear bar supported upon a friction or roller bearing suspended from the bottom of said body, substantially as set forth.

2. The combination, in a front spring-plat-

form for road-wagons, side springs arranged parallel to each other and extended from the axle to the body, the inner ends of said springs being connected by cross-bars, and a fifth-wheel device or king-bolt coupling interposed between said bars and the bottom frame of the body and rearwardly supported upon a roller-bearing, substantially as shown, and for the purpose set forth.

3. The combination, in a spring-platform of the character described, side springs arranged parallel to each other and extended from a fifth-wheel device to the axle, the inner ends of said springs being connected by cross-bars F and II, said bars being "bridge-braced" by the lower cross-bars F' II', the latter adapted to ride upon a friction or roller bearing suspended from the bottom of the body, substantially as shown and described.

4. The combination, in a front spring-platform for road-wagons, side springs arranged parallel to each other and extended from the bottom of the body to the axle, the rear ends of said springs being connected to the body by a fifth-wheel device supported at the rear of the king-bolt upon a friction or roller bearing suspended from the bottom of the body, and an intermediate central spring also extended from said fifth-wheel frame to the axle, substantially as set forth.

5. The combination, in a rear spring-platform of the character described, parallel side springs B B, diagonally arranged axle-stays B' B', axle L, and cross-bars T T, which latter are secured to the bottom frame of the body and their outer ends being adapted to maintain the inner ends of said side springs and axle-stays, substantially as shown and described.

6. The combination, in a rear spring-platform of the character described, the parallel arrangement of the side springs B B, the latter having the inner ends of one or more of their main plates B² curved downward to form the seat C³ on which to rigidly secure the inner end of the diagonally-arranged axle-stay B', cross-bar T, and the vertical spool C', interposed between said cross-bar and the spring B', substantially as shown and described.

7. The combination, in a rear spring-platform of the character described, the axle L, arched upwardly at or near its opposite ends, side springs B, having their terminal ends pivotally connected to the under side of the arch at K, and the rear ends of the stays B', shackled to the depressed portion of the axle at K', whereby to carry the rear ends of said springs and stays in different horizontal planes, substantially as and for the purpose shown and described.

In testimony whereof I have signed this specification in the presence of two subscribing witnesses.

CYRUS W. SALADEE.
